(57) **CLAIM**

The ornamental design for a paper guide for a point of sale terminal, as shown and described.

DESCRIPTION

FIG. 1 is a left side perspective view of the paper guide for a point of sale terminal;

FIG. 2 is a top side plan view of the paper guide for a point of sale terminal;

FIG. 3 is a front side plan view of the paper guide for a point of sale terminal;

FIG. 4 is a bottom side plan view of the paper guide for a point of sale terminal;

FIG. 5 is a left side plan view of the paper guide for a point of sale terminal; and,

FIG. 6 is a rear side plan view of the paper guide for a point of sale terminal.

The broken lines shown in FIG. 1 are for illustrative purposes only and form no part of the claimed design.
